UNITED STATES PATENT OFFICE.

WILLIAM MALLINSON, OF HALIFAX, ENGLAND, ASSIGNOR TO JOSEPH WILD & CO., OF NEW YORK CITY.

DESIGN FOR A CARPET-PATTERN.

Specification forming part of Design No. 5,335, dated October 31, 1871.

To all whom it may concern:

Be it known that I, WILLIAM MALLINSON, of Halifax, in the county of York, England, have invented a new and original Design for Carpet, of which the following is a specification:

The nature of my design is fully represented in the accompanying photographic illustration and sketches, to which reference is made.

I claim as my invention—

The design for a carpet, as shown.

WILLIAM MALLINSON.
